Primary Examiner — Rob Spear*Assistant Examiner* — Carla Wright(74) *Attorney, Agent, or Firm* — Nixon & Vanderhye, P.C.(57) **CLAIM**

The ornamental design for a repeater for communication, as shown and described.

DESCRIPTION

FIG. 1 is a front, top and right side perspective view of a repeater for communication showing our new design with the bottom stands in a stored condition;

FIG. 2 is a rear, bottom and left perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, a left side view being a mirror image thereof; FIG. 8 is a front, top and right side perspective view thereof with the bottom stands in an extended condition;

FIG. 9 is a rear, bottom and left perspective view thereof;

FIG. 10 is a front view thereof;

FIG. 11 is a rear view thereof;

FIG. 12 is a top plan view thereof;

FIG. 13 is a bottom plan view thereof; and,

FIG. 14 is a right side view thereof, a left side view being a mirror image thereof.
